PROCESS OF MANUFACTURING GASOLINE

James R. Rose, Edgeworth, Pa., assignor of
three-fourths to Michael L. Benedum and
Joseph C. Trees, Pittsburgh, Pa.

Application November 19, 1936, Serial No. 111,654

1 Claim. (Cl. 196—10)

This invention relates to a process of extracting gasoline from the gases resulting from the cracking of oil in the manufacture of gasoline, and has for its general object to obtain a maximum recovery of gasoline from such gases and to accomplish such recovery in an economical and efficient manner.

The gases resulting from the cracking of oil in the manufacture of gasoline are known to the trade as "still gases", "receiver gases" and "stabilizer gases", and contain unsaturates varying in richness (such as acetylene, propylene, butylene, etc.) and varying in proportions, according to the grades of the oils cracked.

For convenience of description, the gases treated will be referred to in the claims as "still gases". Hitherto these gases have been allowed to go to waste, except as to such relatively small proportions of the same as may have been employed in the heating of the various units in the cracking plants. By virtue of my invention, I am enabled to reconstruct these gases by the treatment set forth hereinafter, thereby to produce gasoline therefrom on a commercial basis; that is, on a basis which will yield a high proportion of gasoline at low cost.

My process will be described in connection with the drawing, which shows a diagrammatic or schematic representation of an apparatus whereby it may be realized.

The mixture of gases resulting from the cracking of the oil, hereinafter designated "still gases", is delivered through a suitable pipe 1 into a gas holder 2, under a pressure slightly above that of the atmosphere. From this holder, the gases are conducted to a compressor 3, where they are subjected to a pressure of from 200 lbs. to 1500 lbs. per square inch and are delivered under this pressure into a suitable heating stove 4, where the temperature is raised from 200° F. to 1500° F.

The mixture of gases is then conducted, while still under the pressure noted, through one or more catalyst chambers 5 and are delivered thence to a cooler 6, which effects a partial condensation of the gases so treated into liquid form, this condensation into liquid form having been facilitated by the two preceding steps which cooperate to dissociate the unsaturates and recombine the dissociated constituents thereof into gasoline.

The pressures and temperatures vary between the limits stated hereinbefore in accordance with the proportions of heavier unsaturates in the particular gaseous mixture which is to be treated and in accordance with the character of the catalyst to which they are subjected, it being a matter

of common knowledge that the temperatures to which a catalyst must be heated in order to insure a suitable reaction and the pressures to which gases must be subjected in order to pass them through a catalyst will vary with the particular catalyst employed.

The liquid condensed from the gases and whatever gases may have been uncondensed are conducted through a pressure-reducing valve 7 into a receiver 8, wherein further non-condensable gases will pass out through the top of the receiver into a pipe 9. The gases in this pipe may be delivered in whole or in part either to the atmosphere or into the pipe 1 through the pipe 10, by suitable manipulation of the pressure regulating valves 11 and 11'. The gases delivered from the receiver into the pipes 10 and 1 will be collected in the holder 2 for the purpose of being recycled, together with the incoming waste gases from the cracking operation. The pressure reducing valve 7, which is located at the outlet from the cooler, serves to reduce any pressures which may exist in the cooler and in the catalyst chambers to approximately 150 lbs. per square inch, and this pressure, being necessary for the stabilization of the product, is maintained in the subsequent steps of my process.

By recycling the gases, a further separation is accomplished as to the unsaturates that may not have been reconstructed and condensed in their first run through the process.

The liquid (gasoline) in the bottom of the receiver is delivered by means of a charging pump 12 and a pipe 13 into a stabilizing tower 14, for the purpose of stabilizing the product under the pressure noted and of effecting, by means of a condenser 15, a further condensation of such gases as may have been separated from the product. From the condenser what are known as "dry" gases may be delivered through the pipe 16 and the automatic regulator valve 17 to the stills for use in the heating operations.

By raising the temperature to 1000° to 1500° F., a considerable quantity of the saturates are broken down, as well as the unsaturates, and are thereafter cooled and condensed and pumped into the stabilizing tower, as explained hereinbefore, where they are reboiled in order to separate the heavier from the lighter ends.

A catalyst which I have found particularly efficient in the realization of my process is one made from ground phosphate rock, mixed preferably in equal proportions by weight with what is known to the trade as "fire bond" (a mixture of silica sand and water glass). This mixture of

phosphate rock and fire bond is then thoroughly mixed with water, and is then dried and broken into lumps. While the proportions specified hereinbefore for the phosphate rock and fire bond in the catalyst will result in a product which has given satisfactory results at temperatures of approximately 800° F., these proportions may be varied to accommodate variations in the particular unsaturates and mixtures thereof which are treated.

Having thus described my invention, what I claim is:

The process of manufacturing gasoline from still gases which consists in heating said gases to a temperature between 800° and 1500° F. and

under a pressure of from 200 lbs. to 1500 lbs. per square inch; passing the gases thus heated and while under the said pressure in contact with a catalyst comprising a dried mixture in substantially equal proportions by weight of phosphate rock and fire bond; cooling the gases while under the said pressure thereby to effect a preliminary separation of condensable products; reducing the pressure on the said gases and condensable products and delivering them into a receiving chamber; recycling gases evolved in said chamber; and stabilizing the condensable products under super-atmospheric pressure.
